UTILITY KNIFE HANDLE

Ronald L. Gerson, Newton, and Lawrence A. Caprio,
Whitman, Mass., assignors to Louis M. Gerson Co.,
Inc., Middleboro, Mass.

Filed July 15, 1974, Ser. No. 488,478

Term of patent 14 years

Int. Cl. D8—03

U.S. Cl. D8—107

FIG. 1

FIG. 2

FIG. 3

FIG. 4

FIG. 5

FIG. 6

FIG. 1 is a left side view of a utility knife handle in accordance with the present invention showing a razor blade mounted therein in dotted outline for illustrative purposes only;

FIG. 2 is a top plan view thereof;

FIG. 3 is a bottom view thereof;

FIG. 4 is a right side view thereof;

FIG. 5 is a front view thereof; and

FIG. 6 is a rear view thereof.

We claim:

The ornamental design for a utility knife handle, as shown and described.
